PIKE POLE

Thomas J. Crowley, Boston, Mass., assignor, by mesne assignments, to "Automatic" Sprinkler Corporation of America, Cleveland, Ohio, a corporation of Ohio
Filed June 24, 1965, Ser. No. 466,628
1 Claim. (Cl. 294—19)

This invention relates to pike poles for use as fire fighting instruments and more particularly to a novel and versatile lightweight metal pike pole. Pike poles have been universally employed by firemen for centuries, their very name signifying their antiquity as well as their probable origin. These instruments have many diverse uses but are primarily employed to break through and/or tear away building structures such as plaster walls, lathing and the like to expose hidden fires in burning buildings, ventilate portions of burning buildings or probable sources of re-ignition in situations where the original fire has been extinguished.

In prior art poles of this type, the handle has been normally rigid and normally constructed of wood or like material. Because of the rigid construction of prior art pike poles and since the pole handle must be of sufficient length to give the fire fighter capability of reaching extremities in a room or enclosure, the pike poles of the prior art have heretofore been rather unwieldy for operation in small enclosed areas such as closets or in situations where its capability is limited by the closeness of walls or similar obstructions. In addition, since the pikes or tools mounted on the prior art handles are of much greater density and relative weight than a like portion of the handle, a certain top heaviness was inherent in longer poles.

It is therefore an object of this invention to provide a pike pole which can be utilized in situations where maximum reach is required as well as in situations where minimum working room is available by furnishing a handle which can be telescoped or extended according to the requirements of the particular job to be accomplished. The handle portion can be made of a strong lightweight metal, such as aluminum, of sufficient linear unit weight to overcome the top heavy condition of the prior art devices.

It is another object of this invention to provide a pike pole which can be quickly and easily adjusted to a plurality of working lengths.

It is a further object of this invention to provide a device for telescopicable pike poles wherein the telescoping portions thereof are quickly and simply adjustable between working positions while relative rotation between the elements is effectively prevented.

These and other objects of the invention will become better understood by reference to the following detailed description when viewed in the light of the accompanying drawing wherein like numerals indicate like parts throughout the figures thereof and wherein:

FIGURE 1 is a side elevational view of a pike pole in accordance with the invention partly in section and partly broken away, showing the pole in its extreme elongated configuration in solid lines and in a shortened condition in phantom;

FIGURE 2 is an enlarged fragmentary view of a portion of the pole of FIGURE 1; and

FIGURE 3 is a sectional view taken along the line 3—3 of FIGURE 2.

Turning now to FIGURE 1 of the drawings for a more complete understanding of the invention, a pike pole in accordance with the invention is shown in solid lines in its configuration and in phantom lines in a shortened elongated condition. The pole comprises a handle shown generally at 10 with a rake or hook 12 affixed to one end

2

thereof. The handle 10 is formed of two component parts, a tubular segment 14 telescopically receiving an elongated segment 16. The rake 12 is made of an annealed, malleable iron highly resistant to deformation. The rake is press-fitted or otherwise fixedly secured to the outer end of segment 14 while the segments 14 and 16 are made of a lightweight metal, preferably aluminum. As shown in FIGURE 1, the rake is formed in the shape of a pointed hook but can be configured otherwise as may be required for other particular jobs. A key pin 20 extends through the wall of the tubular segment 14 to cooperate with a slot 18 longitudinally disposed in the elongated segment 16. A lock pin 22 is insertable through orifices 26 and 28 suitably disposed in the tubular segment 14 and the elongated segment 16 respectively as will be described in greater detail below. A flexible retaining member 24 is affixed to the head of the lock pin 22 and to the outer surface of the tubular segment 14 to retain the lock pin 22 when it is not in use or when it is disengaged.

20 A pair of hand grips 23 are preferably provided at spaced points on the exterior of the segment 14 to provide a suitable gripping surface for the pole user. In the preferred embodiment the grips 23 are formed from convolutions of cord, preferably of a bright red or other suitable attention-attracting color.

25 In FIGURES 2 and 3 an enlarged view of the juncture between the segments 14 and 16 is shown to illustrate, with greater clarity, details of the structure thereof. As seen particularly in FIGURE 3, the key pin 20 is threaded 30 in a hole tapped through the wall of the tubular segment 14 and extends into the slot 18 of the elongated segment 16. This structure prevents relative rotation of the segments 14 and 16 while allowing telescoping motion therebetween. The slot 18 is a length suitable to provide for 35 full movement between the elongated and shortened configurations shown in FIGURE 1 and serves, in conjunction with the key pin 20, to provide a stop at at least the extreme elongated configuration of the pike pole.

40 Referring now particularly to FIGURE 2 of the drawings, a set of aligned lock pin receiving holes 26 are provided through the walls of the tubular segment 14. A similar set of lock pin receiving holes 28 are disposed through the elongated segments 16 and are oriented with respect to the slot 18 so that the holes 26 and 28 may be 45 brought into alignment by proper telescoping motion between the segments. As will be seen more clearly in FIGURE 1 of the drawings, at least one set of holes 28 is provided proximate the end of the elongated member 16. The sets of holes 28 are preferably disposed longitudinally with respect to the ends of the slots 18 so that they are in alignment with the holes 26 when the key pin 20 is 50 engaged either end of the slot 18. A resiliently biased retaining member 30 is provided on the free end of the lock pin 22 to restrain the pin against accidental withdrawal 55 from the lock pin receiving holes. This member may be in the form of spring loaded detents or may be, as shown, in the form of a snap ring which will compress to provide for withdrawal of the lock pin 22 when a suitable pulling force is exerted upon the pin.

60 In operation and starting with the pole in its shortened configuration, as shown in phantom in FIGURE 1, a configuration which is necessary for use in close spaces, the pin 22 is withdrawn from the holes 26 and the holes 28 proximate the rake end of the elongated member 16. 65 The elongated segment 16 is then withdrawn from the tubular segment 14 until the pin 20 engages the end of the slot 18 most remote from the rake end of the elongated member 16. At this point the holes 26 and 28 are 70 in alignment and the pin 22 is then reinserted to lock the segments in the elongated configuration as shown in FIGURE 1.

The relative thickness of the telescoping members 14 and 16 with respect to the hook-tool can be seen in FIGURE 1. Although the handle portion is sufficiently slim for efficient gripping, the linear unit weight is sufficiently high to overcome top heaviness even when the handle is extended.

It should be obvious that additional sets of holes 28 could be provided throughout the length of the elongated segment 16 if desired, to furnish a pike pole with any desired number of adjustable lengths. In any event, this invention furnished a pike pole which is adjustable to at least two different lengths and is usable at its full strength in either of the lengths selected by the user. By the interrelationship of the arrangement of the key slot and the locking pin holes, the lock pin receiving holes of the respective segments are easily and quickly alignable in the event that rapid adjustment of the pole is required. Since the pole is of metal, the manufacture of an adjustment feature is facilitated and the resulting product will withstand temperatures which would normally ignite or char, and thereby weaken wooden handles.

The specific embodiment set forth above is illustrative and is primarily intended to enable those skilled in the art in understanding the teachings of the invention. It should therefore be obvious, in the light of the above 25 teachings that within the scope of the appended claim, the invention may be practiced otherwise than as specifically described.

What is new and desired to be protected by Letters Patent of the United States is:

A pike pole comprising a tubular segment, an elongated segment telescopically disposed within said tubular segment, a rake fixed to one end of said elongated segment, said elongated segment having a slot longitudinal-

ly disposed in the outer surface thereof and extending to points proximate each end thereof, and inwardly extending key on the inner surface of said tubular segment, said key projecting into said slot to fixed relative rotational 5 alignment between said segments and to stop continued telescoping motion between said segments at the extended and retracted extremes thereof by contact with the ends of said slot, a lock pin, said tubular segment having a pair of transversely aligned lock pin receiving holes therethrough, said elongated segment having a pair of transversely aligned lock pin receiving holes proximate either 10 end thereof, the relative disposition of said pairs of holes, said key and the end of said slot being such that one of said pairs of holes in said elongated segment is aligned 15 with said pair of holes in said tubular segment when said key engages either end of the slot in said elongated segment, said lock pin positively fixing telescoping motion between said segments when inserted through the aligned lock pin receiving holes.
